ELECTRIC SHAVER

Norman A. Steinkamp, Chicago Heights, Ill., assignor to Sunbeam Corporation, Chicago, Ill.

Filed Jan. 15, 1973, Ser. No. 323,564

Term of patent 14 years

Int. Cl. D28—03

U.S. Cl. D95—3 A

FIG. 1 is a perspective view of an electric shaver showing my new design;

FIG. 2 is a side elevational view thereof;

FIG. 3 is a rear elevational view thereof;

FIG. 4 is a top plan view thereof; and

FIG. 5 is a bottom plan view thereof.

I claim:

The ornamental design for an electric shaver, as shown.
